UNITED STATES PATENT OFFICE.

RAYMOND G. MOORE, OF BRIDGEPORT, CONNECTICUT, ASSIGNOR TO THE BASSICK COMPANY, OF BRIDGEPORT, CONNECTICUT, A CORPORATION OF CONNECTICUT.

DOOR LATCH.

Application filed November 21, 1921. Serial No. 516,620.

To all whom it may concern:

Be it known that I, RAYMOND G. MOORE, a citizen of the United States, and resident of Bridgeport, in the county of Fairfield and State of Connecticut, have invented certain new and useful Improvements in Door Latches, of which the following is a specification.

This invention relates to certain new and useful improvements in door latches. The primary object of the invention is to provide a simple and effective construction whereby the operation of the door tends to force the door firmly against its seat so as to prevent rattling. The improved device is particularly adapted for use as an automobile door latch but may be used to advantage in connection with such doors as refrigerator doors in which it is particularly desirable to have a tight closure and to doors generally, such for example as the doors of buildings in which the wind is likely to cause rattling.

I accomplish the desired purpose by the use of a sliding bolt mounted to slide forwardly into the striker recess, when the door is closed, at an angle to a surface within the recess against which a surface of the outer end portion of the bolt will engage. As this surface of the bolt slides into engagement with the interior surface of the recess and moves somewhat over the same, the opposite side of the bolt will press the door firmly against its seat, by a simple camming action.

Other objects of the invention consist in the provision of improved combinations of parts and construction of elements, all as will appear more fully hereinafter in the following specification and be particularly pointed out in the appended claims.

In order that a clearer understanding of the invention may be had attention is hereby directed to the accompanying drawings forming part of this application and illustrating by way of example one form of the invention. In the drawings,

Fig. 1 is a side elevation of a latch construction embodying the invention;

Fig. 2 is a horizontal section taken on line 2—2 of Fig. 1, showing the latch bolt when the latter is just beginning to enter the striker recess;

Fig. 3 is a similar view showing the latch bolt extended further into the recess;

Fig. 4 is a similar view showing the latch bolt fully projected into the striker recess so as to force the door into firm engagement with its seat, and

Fig. 5 is a section taken on line 5—5 of Fig. 1.

Referring to the drawings, I have illustrated the bolt as mounted within a usual form of bolt chamber, it being understood that such construction is not essential, but only that some suitable form of guiding means be used whereby the bolt will be guided for sliding movement forward and back at a desired angle. The latch casing, or plate 1 is shown as provided with the operating hand lever 2 pivoted to plate 1 by means of hub 3, which may be provided with a square opening to receive the shank of an operating handle or knob (not shown). Lever 2 is shown as urged forward by means of a spring 4 which bears thereon, this spring being secured to the casing in any convenient manner as by means of the struck-up tongues 5, 5, bent over the tail portion of the spring to clamp the same to the plate.

A bolt chamber or guiding means for the bolt is provided, in the embodiment of the invention illustrated herein, by depressing a portion of the plate 1 to form a slideway or runway 6 which extends at an acute angle to the surface 7 of the door 8 to which the main portion of plate 1 is illustrated as secured. In the structure shown, runway 6 also extends at an inclination to the front edge 71 of the door. The bolt chamber 9 is shown as completed by a plate 10 which extends forwardly in parallel relation to the runway 6, a suitable inclined cut-out being provided within the body of the door to receive the plate 10. The bolt chamber, in the embodiment of the invention illustrated, is thus provided by forming an inclined runway partly within the body of the door and partly exterior thereto, it being only essential, however, as stated above, that bolt guiding means be provided carried by the door at a suitable inclination for accomplishing the purpose referred to.

The bolt 11 is slidably mounted within the chamber thus provided, the bolt being illustrated as having an enlarged rear portion 12 and a forward portion or nose 13, both of which portions are adapted to slidingly

fit within the bolt chamber. The bolt is provided with a portion 11¹ extending between the front and rear portions 13 and 12, of less width than the portions 13 and 12, so as to provide a space 14 in which the hand lever 2 may operate. This hand lever extends through slots in the walls of the bolt chamber so as to extend through the chamber forwardly of the rear enlargement 12. The hand lever is accordingly adapted to be pressed against the forward surface of the enlargement 12 to retract the bolt.

The bolt is spring pressed into its projected position, in the embodiment of the invention illustrated, a coiled spring 15 being illustrated as secured to the plate 1 at 16, this spring having an end portion 17 which extends through a slot in the wall of the bolt chamber into position to bear 20 against the rear surface of the portion 12 of the bolt.

I have illustrated the door jamb 18 as provided with the usual striker plate 19, the jamb having a keeper recess 20 into which the forward end of the bolt will extend when the door is closed. A portion of the striker plate 19 is bent to extend into the recess to form a bearing plate 21 extending along one interior lateral surface of the recess. The door jamb is also provided with a contact plate or stop 22, against which the door will seat when closed, this plate providing a surface which is oppositely disposed in relation to the bearing plate 21. One edge of the nose 13 of the bolt is provided with a beveled face 23.

It is believed that the operation of the device will now be clear. When the door is closed the beveled surface of the nose of the bolt will ride over the striker plate 19, the bolt being retracted into its compartment against the pressure of spring 15, until the bolt is in alignment with recess 20. Spring 15 will then press the bolt into the keeper recess, the bolt sliding forward along a path which is parallel to the surfaces indicated at 6 and 10. These surfaces are inclined, preferably at a comparatively small acute angle, to the main body portion of the plate 1 and 50 similarly to the bearing plate 21 within the keeper recess. Accordingly as the bolt moves forward a surface of the bolt will slide into engagement with the bearing plate 21 within the keeper recess.

55 Preferably the nose of the bolt is provided with a lateral surface 24 which is approximately parallel to the surface of bearing plate 21. When the nose of the bolt first enters the keeper recess this surface 24 of the bolt will be a slight distance away from plate 21, as is shown in Fig. 2. Upon a slight further movement of the bolt, surface 24 of the bolt will come into engagement with plate 21, as is indicated in Fig. 3. Upon 65 a further movement of the bolt under the

force of spring 15, surface 24 of the bolt will slide somewhat along plate 21, this action resulting in forcing the bolt and the surface 6 upon which it rides laterally towards the seating surface 22 so that the door will 70 firmly seat against the seating member 22. This final position of the bolt is indicated in Fig. 4 in which for purposes of illustration the portion 6 of the bolt casing is indicated as being seated firmly against the 75 member 22, it being understood that the body of the door is pressed firmly against the stop 22, usually of course with rubber bumpers, or the like, interposed. The action of the bolt is sufficient under the impulse of 80 its spring to wedge or cam the door so firmly against its seat as to prevent rattling of the door in operation. At the same time the pressure is readily released by a slight backward movement of the hand lever 2 so that 85 operation of the device will be easy.

It should be understood that the invention is not limited strictly to the details of construction described but is as broad as is indicated by the accompanying claims.

90 What I claim is:—

1. In a door latch, the combination of a door jamb having a striker having a lateral surface, an abutment against which the door seats when closed, a door having a plate 95 thereon extending at an angle to said lateral surface, when the door is closed, a bolt slidably mounted on said plate, and means for operating said bolt to project the same at an angle to said lateral surface, to force the 100 outer end of the bolt against said surface, and thereby cause the bolt to press the door firmly against its said seating abutment, said plate and bolt being constructed to cause the bolt to travel as a whole at an angle 105 to said lateral surface throughout its entire movement of projection.

2. In a door latch, the combination of a striker on a door jamb, said striker having a lateral surface, and an abutment against 110 which the door seats when closed, a door having a plate thereon extending at an angle to said lateral surface, when the door is closed, a bolt slidably mounted on said plate, to move parallel thereto throughout its 115 whole length and for its entire movement, means for retracting said bolt, and spring means for projecting said bolt to press the outer end of the same against and over said lateral surface, and thereby cause the bolt 120 to press the door firmly against its said seating abutment.

3. In a door latch, the combination of a plate adapted to be secured to a door, having a portion adapted to extend parallel to a 125 lateral surface of the door and a portion extending at an acute angle to said first portion, forming a bolt runway, a bolt slidable over said runway, means for guiding the bolt, and means for operating the bolt. 130

4. In a door latch, the combination of a plate adapted to be secured to a door, having a portion forming a bolt runway adapted to extend at an acute angle to a lateral surface of the door and at an obtuse angle to the forward edge of the door, and portions adapted to be secured to the door so as to hold the runway portion at the desired angle, a bolt slideable over said runway, and means for guiding and operating said bolt. 10
- 5 Signed at Bridgeport in the county of Fairfield and State of Connecticut this 18th day of November A. D. 1921.

RAYMOND G. MOORE.
